UNITED STATES PATENT OFFICE

20,351

TIRE DEFLATION INDICATOR

George B. Rodney, San Antonio, Tex.

Original No. 1,984,084, dated December 11, 1934,
 Serial No. 685,889, August 19, 1933. Application
 for reissue December 7, 1936, Serial No.
 114,674

3 Claims. (Cl. 200—58)

(Granted under the act of March 3, 1883, as
 amended April 30, 1928; 370 O. G. 757)

This invention described herein may be manufactured and used by or for the Government for governmental purposes, without the payment to me of any royalty thereon.

5 This invention relates to a deflation indicator for pneumatic tired vehicles.

The principal object of the invention is to provide an apparatus for notifying the operator of the vehicle of the deflation of any tire below a predetermined pressure.

10 Many automobile accidents are caused by the deflation of a tire which so affects the control of the vehicle that it is practically impossible for the operator to hold the same on the road. It is not necessary that the deflation be instantaneous, as when a "blow-out" occurs, to cause a rapid skidding from the road bed, since a side drag will develop from a slow leak, and may become disastrous if the car is travelling at a high rate of speed. It is to prevent just such accidents that the applicant designed the apparatus which forms the subject matter of this application, for if the operator can be notified of the deflating of any one tire he can reduce his speed to prevent the 25 unbalanced vehicle from being thrown from the road.

Briefly stated, my invention consists of pressure switches which are attached to each of the vehicle tires. These pressure switches operate 30 with either deflation or inflation of the tire and when a predetermined pressure is reached, make circuits in which are connected indicating lights.

Having thus briefly described the invention, the same will now be described in detail and reference for this purpose will be had to the accompanying drawing in which corresponding parts are indicated by like reference numerals:

35 Fig. 1 is a sectional view of the pressure switches showing the central stem in the position caused by deflation of the tire;

40 Fig. 2 is a similar view to Fig. 1 showing a slightly modified form adaptable to also indicate overinflation. In this figure the central stem is shown in a position corresponding to normal inflation of the tire.

The detail construction of the pressure switch, particularly that type which functions only with deflation of the tire as shown in Fig. 1, will now be considered. This switch is composed of the 50 following members: An outer main stem (23) which is cylindrical in form and flanged at its lower extremity, the cylindrical portion is threaded externally for the reception of the adjustable metallic cap (24) and the lock nut (25) for retaining cap (24) in any desired position.

Slidably mounted within the main stem (23) is fitted the plunger (26) which is made of brass or any other suitable material. This plunger (26) is solid and of circular cross-section and terminates at its lower extremity into a disc (27) having a lower spherical surface (28). The exterior surface of plunger (26) and the upper surface of disk (27) are protected against short-circuiting contact with the main stem (33) by an insulator (29) which consists of an insulating sleeve (50) and a disk (51), of insulating material, the disk forming a lateral extension of the lower end of the sleeve, as clearly shown in Fig. 1 of the drawing. The upper end of the central stem (26) is threaded for the reception of the adjustable contact nut (30) and the internally threaded bushing (31). The extension of the main stem (23) and the central stem disc (27) are enclosed by a rubber cover (32) in order to protect the inner tube (33) of the tire (34) from coming in contact with the metal parts.

The top of the adjustable cap (24) is drilled for the reception of a contact terminal (35) which is insulated from the cap by the insulator (36) comprising a flanged cylindrical member (37) 25 and a centrally drilled disc (38).

Surrounding the bushing (31) and connected to the insulated terminal (35) and abutting the adjustable contact nut (30) is a helical spring 30 which tends to force the central plunger 35 downward against the resistance of the air pressure in the inner tube of the tire. On deflation of the tire the spring overcomes the decreased resistance and moves the plunger radially inward, until the adjustable contact nut (30) abuts the top of the main stem (23). Since the main stem (23) is grounded through the rim the contact between the nut (30) and the main stem (23) establishes a circuit to the indicator, the current passing through the spring (39), terminal (35), conductor (15), through other suitable conductors to the indicator located on the instrument panel. Neither the last mentioned conductor nor the indicating instrument are shown in the drawing, since no novelty of construction or operation 45 resides in this supplementary apparatus.

In the operation of the entire device the deflation of any tire causes the particular pressure switch to function and thus establishes a circuit to the particular signal device on the instrument 50 board to indicate the location of the deflating tire.

The indicating instrument may consist of a battery of lights which are illuminated coincident with the deflation of the tires. Thus if the 55

right front tire deflates below a predetermined amount, say 20 pounds, a particular light will glow; the position of the light determining the location of the deflating tire. Instead of a light indicator, an electro-magnetically operated pointer indicator may be used or any convenient type suitable for location on the instrument board.

Setting the device for operation at any predetermined pressure is extremely simple; for example, suppose the normal pressure of the tires is thirty pounds, and it is desired that the signal operate when the tires are deflated to a pressure of twenty pounds. The method of procedure is as follows: Inflate all tires to a pressure of twenty pounds then screw down each of the caps (24) until the signal operates, lock the cap at this height by turning the lock nut (25) tight against the bottom of the cap and then proceed with the inflation of the tires up to the required thirty pounds of pressure. As soon as the tires are further inflated the operation of the signal will cease and it will not operate again until the tires are deflated to twenty pounds pressure.

Although the primary object of the invention is to indicate deflation of any tire, a modified form of the device may be constructed which will also indicate overinflation. The modification consists in eliminating the extension (51) from the cover (29) as shown in Fig. 2. When this extension is omitted overinflation causes the pressure within the tire tube (34) to raise the plunger (26) until the top of the disc (27) touches the lower surface of the flanged extremity of the main stem (28), making a circuit through the grounded main stem (28) to the indicator, as described above.

It is obvious that those skilled in the art may vary the details of construction and arrangement of parts without departing from the scope and spirit of the invention, and therefore it is not desired to be limited to the foregoing description except as may be required by the claims.

Having described my invention, what I claim as new and wish to secure by Letters Patent is:

1. A pressure responsive switch adapted to be mounted in the rim of an automobile wheel, said switch comprising an externally threaded metallic main stem having one end extended through and clamped to the radial outward surface of said rim, a central plunger comprising a stem threaded at its upper extremity for the reception of a contact nut, said contact nut having a flanged extremity adapted to serve as an electrical contact surface in conjunction with the upper extremity of the main stem, a cylindrical insulating sheath surrounding the unthreaded portion of the plunger stem and slidably mounted within said main stem, the stem of the plunger terminating at its lower end in a disc, insulating means extending from the lower end of the sheath and overlying said disc to insulate the upper sur-

face of said disc against short-circuiting contact with the main stem, a cap adjustably fitted to the main stem, means for retaining said cap in any predetermined position along said stem and a spring interposed between the flange of the contact nut and the top of the cap, and an insulated terminal fitted in the top of said cap and connected to said spring.

2. A pressure responsive switch adapted to be mounted in the rim of an automobile wheel, said switch comprising an externally threaded metallic main stem having one end extended through an opening in the rim, said end being clamped to the radially outward surface of said rim, a central plunger slidably mounted within the main stem and including a stem threaded at its upper extremity for the reception of a contact nut, said contact nut having a flanged extremity adapted to serve as an electrical contact surface in conjunction with the upper extremity of the main stem, a cylindrical insulating sheath surrounding the unthreaded portion of the plunger stem and slidably mounted within said main stem, the stem of the plunger terminating at its lower end in a disc of greater diameter than the insulating sheath; the upper surface of said disc and the adjacent surface of the main stem serving as electrical contact surfaces, a cap adjustably fitted to the main stem and means for retaining said cap in any predetermined position along said stem, a spring interposed between the flange of the contact nut and the top of the cap to react against the plunger, the compressive resistance of said spring depending on the adjustment of the cap and an insulated terminal fitted in the top of said cap and connected to said spring.

3. A pressure responsive switch adapted to be mounted in the rim of an automobile, said switch comprising an externally threaded stem, having one end extending through and clamped to the radially outward surface of said rim, a central plunger including a member slidably mounted within the stem and terminating at its lower end in a disk, the slideable member and disk being insulated against short-circuiting contact with said stem, a contact nut positioned on the plunger member, adjacent its upper end, said nut upon depression of the plunger being adapted to engage the upper extremity of said stem, and establish an electrical path between the stem and the plunger member; a cap internally threaded for engagement with said stem, means in connection with the stem and coacting with the cap whereby threaded engagement of the cap with the stem is restricted to a point on the latter determined with reference to a selected inflation pressure, a spring interposed between the contact nut on the plunger member and the top of said cap, and an insulated terminal fitted in the top of the cap and connected to said spring.

GEORGE B. RODNEY.
